UNITED STATES PATENT OFFICE.

JOHN W. BARWELL, JEROME WARD, NICOLAY NELSON, JOSEPH HINGHER, WALTER E. BOOTH, AND WILBUR L. BLOWS, OF WAUKEGAN, ILLINOIS, ASSIGNEES TO BLATCHFORD CALF MEAL COMPANY, OF WAUKEGAN, ILLINOIS, A CORPORATION OF ILLINOIS.

FEEDING APPARATUS.

Specification of Letters Patent. Patented May 30, 1922.

1,418,267.

Application filed April 17, 1919. Serial No. 290,723.

To all whom it may concern:

Be it known that we, JOHN W. BARWELL, JEROME WARD, NICOLAY NELSON, JOSEPH HINGHER, WALTER E. BOOTH, and WILBUR L. BLOWS, citizens of the United States, residing at Waukegan, in the county of Lake and State of Illinois, have invented certain new and useful Improvements in Feeding Apparatus, of which the following is a specification.

This invention relates to a device or apparatus for feeding grain or the like, to mills and for separating stones, nails, pieces of iron or other hard or heavy objects from the material which is being fed. This device is particularly applicable to centrifugal mills having suction feeds, but may be used in connection with any mill or wherever it may be utilized, by providing suitable suction for drawing air and the material to be fed, through the feeding device.

The objects of this invention are to provide a new and improved form of feeding apparatus; to provide a feeding apparatus having a novel feed adjusting mechanism; to provide means for separating stones, pieces of metal or the like from the grain; to provide a feeding device having a sight opening; and in general to provide such an improved apparatus as will be described more fully hereinafter.

In the accompanying drawings illustrating this invention:

Fig. 1 is a front view of the feeding apparatus shown in position on a mill;

Fig. 2 is a longitudinal, sectional view taken on the line 2—2 of Fig. 1; and,

Fig. 3 is a detail of the feed regulating plate.

One of the principal features of this invention consists in providing an arrangement whereby a downwardly flowing stream of grain or the like is met by a stream or blast of air and carried into the mill while obnoxious articles are separated from the grain and preferably discharged from the feeder. In the particular form shown in the drawings, 4 indicates a portion of a centrifugal mill having the usual feed opening 5. The feeding apparatus is bolted or otherwise secured to the mill and comprises a lower section 6 and upper section 7, which are bolted together by means of bolts or screws 8, although these sections may be formed integrally if desired. The lower section has end walls 9 and is provided with an inlet aperture 10 for the grain or material to be fed, and with an inlet aperture 11 for the air, it is also provided with an outlet aperture 12 which registers with the inlet aperture 5 of the mill. The inlet aperture is formed by the side walls and by a front wall 13 and a top wall 14, the latter projecting downwardly and inwardly to form the top of the outlet aperture 12. A baffle plate 15 projects inwardly and downwardly from the front wall 13 and coacts with a second baffle plate 16 which projects downwardly and outwardly from the rear of the inlet or aperture 10. The two baffle plates are arranged to provide a relatively long narrow feed opening 17, but the lower end of the plate 16 extends below the plate 15 so that the grain passing through this passageway is directed outwardly and downwardly as indicated by the arrow X. The bottom of the lower section comprises a wall 18 which extends upwardly and outwardly from the feed opening 5 and forms the bottom side of the outlet aperture 12. A second plate or wall 20 connects with, or is a continuation of the plate 18 but extends downwardly and outwardly and terminates at a point 21 somewhat below and inwardly from the lower edge 22 of the baffle plate 16, thus forming a passageway 23. The air inlet aperture 11 is formed by the end walls 9, front wall 13 and a rear wall 24 which is substantially parallel to the wall 13 but has its inner surface curved or concaved as shown at 25 so that the air passing upwardly over its surface will be directed somewhat toward the end 22 of the baffle plate 16 or so as to have a circular or rotary motion in the adjacent portion of the feed device. The lower end of the air inlet passageway is preferably bevelled as shown and is provided with guideways 26 for a slide 27 for regulating the air opening. This slide may be held in adjusted position in any suitable manner but is preferably provided with a lug or projection 28 having a hole for an adjustable stop-bolt or screw 29. This screw passes through a hole 30 in a cross-bar 31 which is secured to the frame or casing and is provided with a nut 32 for holding the same in adjusted position. This provides means for adjusting the air opening which

- will ordinarily be sufficiently wide to permit the discharge of nails, stones or the like, but if any unusually large objects lodge in this trap portion of the apparatus, they 5 may be discharged by pulling up the slide 11 and then the slide may be pushed down until the projection 28 strikes the head of the screw 29 so that it will again come to adjusted position.
- 10 The front wall 13 is provided with a sight opening 33 covered by a glass 34 so that the operation of the feed device may be readily observed without disturbing any of the mechanism.
- 15 The upper section 7 comprises a chute which registers with the inlet aperture 10 of the lower section. A feed roller 35 is mounted on a shaft 36 which passes through the side walls 37 of the upper section and is 20 mounted in suitable bearings 38. This shaft is driven by any suitable means such as a pulley 39 and belt 40. An angle bar 41 directs the material in the upper part of the chute onto the wheel 35 which rotates 25 in the direction indicated by the arrow. A resilient feed plate or guide 41 is secured to the back of the section 7 by screws 42 and its free end tends to swing downward and away from the feed roller or wheel 35.
- 30 The plate is adjusted toward the wheel by means of a set screw 43 passing through the back of the chute. The lower portion of the plate 41 is slit to form fingers 44 as shown in Fig. 3.
- 35 The material to be fed into the mill is supplied to the upper section or chute 7 in any desired manner preferably so that the chute is kept substantially full. The amount of grain to feed may be readily adjusted 40 or regulated by turning the screw 43 to swing the fingers or lower edge of the plate 41 toward or away from the feed roller 35 so as to decrease or increase the discharge passage. It will be noted that, if any hard 45 or unyielding object enters with the material, it will be pressed against one or more of the fingers 44 which will readily yield to admit its being forced through by the wheel so that the entire guide plate 41 does 50 not need to be bent, or swung away from the roller. This will prevent the feed opening from being temporarily enlarged and permitting an excess of material to pass through.
- 55 As the grain or material which is being fed passes through the feed opening 17, it is directed outwardly over the lower end of the plate 16 and falls on the slide 27. It then passes down and over the lower edge 60 of the slide where it is met by the upwardly directed stream of air coming through the air inlet. The downward movement of the grain is stopped by the air and the air and grain then partake of a whirlwind or rotary 65 movement and some of the air and grain
- pass together through the passage-way 23 then up over the wall 20 and then down over the wall or plate 18 into the feed opening 5 of the mill. Other kernels of grain appear to circulate or revolve about in the 70 lower portion of the feed device momentarily before passing into the outlet 23. If pieces of metal, stones or the like, are permitted to pass into the mill, they are apt to injure the mill or cause fires to be 75 started therein. Such things, being heavier than the grain, will not be stopped by the air but will drop down to the bottom of the feeding apparatus and pass out through the air inlet. Some of these heavier particles, such as tacks, nails or the like, will 80 pass down along the slide 27 and be caught by the incoming air, and will strike against the curved face 25, and then fall down through the inlet opening. These heavy 85 particles however are on the outer circumference of the whirlwind or air rotating in the lower portion of the device, and may be carried back again onto the slide 27, but will eventually pass out through the opening. This circular or rotary movement however, is exceedingly effective in making the desired separation, and by adjusting the air inlet, it has been found that heavy 90 kernels of grain may be separated from lighter kernels as well as separating heavy 95 foreign particles from the grain. If any unusually large article is caught, it may be discharged by pulling up the slide 27 as above stated.
- 100 The sight opening permits the operator to observe whether the proper amount of grain is being fed and assists in regulating the feed which may be done by adjusting the screw 43. It also permits him to observe whether any large articles have passed into the lower compartment of the feed apparatus and should be removed therefrom.
- 105 It will be seen from this description that we provide an exceedingly simple and convenient feeding apparatus which has been proven in actual operation to be effective in separating heavy objects or articles from the grain and most of these objects are discharged at once from the feeding apparatus so that it is always in operative condition and not apt to become clogged by a collection of such articles. Having thus described our invention, what we claim and 110 desire to secure by Letters Patent is:
- 115 1. A feeding apparatus having a conduit for directing a stream of grain downwardly a conduit for directing a stream of air upwardly to meet the stream of grain to form 120 a rotary movement and a discharge conduit for receiving the air and the grain carried thereby, the arrangement being such that the air will carry all of the grain through the discharge conduit and into a mill or 125

the like while permitting the discharge of heavy objects which will be separated from the grain by the rotary movement of the air and will drop downwardly through the air 5 conduit.

2. A feeding apparatus having a grain inlet in the top thereof, an air inlet in the bottom thereof, and a discharge outlet in the side thereof, and having a passageway 10 formed to cause the upwardly moving current of air to meet the downwardly moving stream of grain to create a rotary movement and carry it through the outlet aperture while permitting heavier objects to 15 drop down and be separated from the grain.

3. A feeding apparatus for mills, comprising a casing having a grain inlet in the top thereof, baffle plates arranged below the inlet for directing the grain downwardly 20 and outwardly, said casing also having an air inlet in the bottom thereof with a passage-way for directing the air upwardly to meet the grain, said passageway being formed so as to create a rotary movement 25 of the air and grain, said casing also having a lateral passage-way through which the air and grain is drawn while permitting heavier articles to fall down through the air inlet.

4. A feeding apparatus comprising a casing 30 having an opening in the top thereof, two baffle plates below the opening forming a transverse narrow passage-way, one of said plates being extended beyond the other to direct the material outwardly, an adjustable air inlet in the bottom of the casing 35 below said passage-way, said casing having a sight opening in the front thereof, said air inlet having a rear wall back of the passage-way with its surface curved to direct the air toward the lower edge of the extended baffle plate, the rear portion of the casing comprising a passage-way extending 40 first upwardly and then downwardly to the outlet aperture.

45 5. A feeding apparatus comprising a casing 6 having end walls 9 and having an inlet

aperture 10, an air inlet aperture 11, and an outlet aperture 12, said casing having a top wall 14 which extends downwardly and inwardly toward the outlet aperture; also 50 having a baffle plate 15 and a baffle plate 16, the latter projecting downwardly and outwardly beyond the plate 15, a front wall 13 having a sight opening with a transparent cover, said air inlet having a rear wall 55 24 with a curved outer face, a slide for said air inlet, means for holding the slide in adjusted position, said casing also having bottom walls 20 and 18 which extend respectively upwardly and then downwardly to 60 the outlet aperture 12, substantially as described.

6. A feeding device of the character described, having a feed passageway for the grain, and having an air inlet having one 65 of its walls formed to cause a rotary movement of the air and grain before passing through the outlet.

7. A feeding device, having a downwardly sloping bottom with an air inlet at the lower 70 edge of the bottom, said inlet having a curved guide portion at one side thereof for causing a rotary movement, the outlet of the feed device being above said curved portion.

75 8. A feeding device of the character set forth, having an adjustable sloping bottom, means for directing the material onto said bottom, said device having an air inlet along the lower edge of the bottom, and having a 80 substantially vertical concave wall along one side of the air inlet, and having an outlet above the wall, the arrangement being such that the material is given a whirling or rotary movement in the lower portion of 85 said device adjacent to said concave wall.
